UNITED STATES PATENT OFFICE.

GILBERT S. VERNAM, OF BROOKLYN, NEW YORK, ASSIGNOR TO AMERICAN TELEPHONE AND TELEGRAPH COMPANY, A CORPORATION OF NEW YORK.

TRANSMITTING HANDWRITING AND PICTURES.

Application filed July 12, 1923. Serial No. 651,111.

To all whom it may concern:

Be it known that I, GILBERT S. VERNAM, residing at Brooklyn, in the county of Kings and State of New York, have invented certain Improvements in Transmitting Handwriting and Pictures, of which the following is a specification.

This invention relates to the secret transmission of intelligence by electric currents or otherwise, particularly the transmission of graphic records consisting of handwriting, diagrams, pictures and the like. The object of the invention is to provide a system for enciphering and deciphering such records, when transmission is to be by electric currents the result is, in general effected by altering the transmitting currents according to some rule or code, so that if the transmission line is tapped the impulses taken off will produce an unintelligible record. At the receiving end, the signal impulses may be restored to their original form before acting upon the receiving device so as to reproduce the original writing or picture at the receiving station, or the enciphered signal impulses may be used to produce the writing or diagram in ciphered form, and this may be deciphered at any desired time or place by the use of suitable apparatus operating according to the same rule or code. The invention may also be used to mechanically encipher handwriting or the like so as to produce a written record in unintelligible form which may then be transmitted electrically or in any other desired manner and deciphered mechanically at the receiving end. The invention will be described more in detail in connection with the accompanying drawings in which Figure 1 represents one form of the invention. Fig. 2 represents a modification in which the enciphering is accomplished mechanically; and Fig. 3 represents a detail of the apparatus shown in Fig. 2.

Referring to Fig. 1, 10 and 11 represent respectively the sending and receiving apparatus of the ordinary telautograph. The sending station 10 comprises two resistance elements 13 and 14 over which travel the rheostat arms 15 and 16 which are controlled by link motions from the point 18 at which may be located a tracing instrument or pencil. Each of the resistances constitutes a potentiometer connected across the battery 20, and the arms 15 and 16 are

connected respectively to transmission lines 21 and 22. As is well known, this apparatus serves to transmit over the lines 21 and 22 varying currents representing respectively components of the movement of the point 18. In the ordinary telautograph system these varying currents act upon receiving magnets 24-25 which are attracted by a permanent magnet or an electromagnet 26, thus moving the recording pencil 29 through operation of links 30 and 31, to reproduce the figure traced by the pencil at 18.

In accordance with the present invention the currents transmitted by such an apparatus are varied between the transmitting and receiving stations, so that the currents on the line do not represent components of the movement of the point 18 of the transmitting apparatus. In Fig. 1 this is accomplished by imposing upon the lines additional electromotive forces which are varied in a prearranged manner. For this purpose, resistances 34, 35, in the form of closed loops with circularly arranged contact points, may be used, as indicated, with diametrically opposite points on each resistance bridged by a circuit including a battery or other source of potential 36, 37. The line wires 21, 22 are connected to the bridges containing these sources, and the outgoing lines 38, 39 are connected respectively to the arms 40 and 41 which rotate over the contacts of resistances 34, 35, respectively. It may be found desirable to make one or both of the circularly arranged resistance elements vary in amount for given angular distances as is indicated by the variation in the resistance element 35. The arms 40 and 41 may be driven in any predetermined manner and by any convenient means.

At the receiving end are two resistance elements 42 and 43 corresponding exactly to the elements 34 and 35, respectively. Sources of current 44, 45, corresponding to sources 36, 37, are connected across diametrically opposite points of the elements 42 and 43, and each of these elements is provided with a rotating arm 47, 48, corresponding to the arms 40 and 41 at the transmitting station, and controlled by any suitable means so that each will revolve at the same speed as the corresponding arm at the transmitting station. The receiving magnets 24 and 25 are provided with additional wind.

ings 50 and 51 which are connected on one side to ground and on the other to the sources of current 44 and 45, respectively, through the rotating arms and the resistances 42, 43. Regulating resistances 52 and 53 are provided for controlling the effect of the windings 50 and 51.

With the system thus arranged, the additional potentials imposed upon the line currently with the signal impulses are continually varied by the rotating arms 40, 41 with the result that the currents found in the transmitting lines 38, 39, should these be tapped by an unauthorized individual, 15 would not produce an intelligible record when applied to the ordinary telautograph apparatus or any other receiving apparatus unless it were provided with the precise deciphering mechanism herein described. At 20 the receiving station, as described, current impulses are produced by the rotating arms 47 and 48 passing over the potentiometers 42 and 43 which are identical with the variations produced in the signaling impulses by 25 the rotating arms 40 and 41, and these impulses being applied to the coils 50 and 51 in the proper phase relation will exactly counteract in the receiving magnets 24 and 25 the variations produced by the enciphering mechanism, so that the recording pencil 30 29 will produce the handwriting, diagram or other graphic record as it is traced at the point 18.

In Fig. 2 I have shown an arrangement 35 for enciphering mechanically. In this figure, 60 and 61 represent respectively the transmitting and receiving mechanism of the ordinary telautograph. At the transmitting end only the resistances 62 and the link motion 63 for varying the resistances are shown in detail; and at the receiving end only the controlling magnets 64 and the recording link motion 65 are shown in detail. Instead 40 of forming letters or diagrams to be transmitted by tracing them at the point 66, as in the ordinary telautograph, this point of the link motion is connected to one point 68 of a pantograph 69, or some other similar or suitable mechanical movement; and the figure to be transmitted is traced by another 45 point of the pantograph, as at 70. Means are then provided for causing a given movement of the point 70 to be reproduced in the link motion of the telautograph in a varied 50 or changed form. In the apparatus here shown by way of illustration, this is accomplished by connecting the point 68 of the pantograph to the point 66 of the telautograph through an arm 72 which is arranged 55 to be rotated by a gear 73 driven by a rack 74 which has one end fixed to the fixed point 76 of the telautograph. A spring 77, or other convenient means, is arranged to maintain the gear and rack in an engagement. 60 At the receiving end an exactly correspond-

ing pantograph or mechanical movement 80 is arranged to connect the usual recording point 81 of the telautograph to the recording point 82 of the deciphering apparatus.

With the apparatus thus arranged, it will be seen that a given movement of the point 70 at the transmitting end will cause not only a corresponding movement of the point 68 of the telautograph, but will cause a rotation 75 of the gear 73 on the axis 68 due to its engagement with the rack 74. This rotation will, of course, cause the point 66 to produce a movement additional to that represented by the movement of the point 70, this movement being in accordance with the fixed rule 80 represented by the design and arrangement of the gearing here shown. The altered movement of the point 66 will be reproduced by telautograph apparatus at the point 81, so that if the writing or drawing be traced 85 by a recording instrument at either the point 66 or the point 81, it will be in an unintelligible form. The movement of the point 81, in accordance with the movement of the point 66, will, however, cause a movement 90 of the pantograph 80 and the gearing 83-84 connected thereto, which will exactly counteract the enciphering effect of the gearing 73-74 at the transmitting end, with the result that the point 82 will record correctly 95 the figure traced at the point 70.

As heretofore pointed out, the figure may be recorded at the transmitting station in the enciphered form and transmitted in any desired way and deciphered wherever desired 100 by employing an apparatus similar to that used in enciphering. Thus the apparatus shown in Fig. 2 may be used for recording the mechanically enciphered figure at the point 66 or for deciphering messages which have elsewhere been enciphered by a similar 105 apparatus and transmitted to that point by mail or otherwise. And if a message be enciphered mechanically at the point 66, it may be transmitted to the receiving station 110 of Fig. 2 and there deciphered on the apparatus 80. It has been found that when an enciphered figure is to be deciphered by mechanically tracing it in the manner just suggested, there may be points at which the 115 proper direction of movement of the tracing pencil on the enciphered figure is doubtful due to the presence of small loops or crossing lines, or the like. The tracing in such cases is much facilitated if two tracing 120 points are used on both the enciphering and deciphering apparatus. Thus in Fig. 2 I have shown a second tracing point 85 at the left-hand station and a second tracing point 86 at the right-hand station. Each point 125 will produce an enciphered form of the figure traced at the point 70, so that there is, in fact, a double cipher, and when this is to be traced in the deciphering mechanism, the two points of the deciphering mechanism 130

will trace the respective ciphers thus produced. Where there is doubt as to the proper direction of movement on one cipher, reference may be made to the other to solve the difficulty. A handle 87 may be provided on the axis of the gear to facilitate its rotation when tracing the figure in mechanical deciphering.

It is to be understood that the forms of the invention here shown are merely illustrative. Obviously any electrical apparatus suitable for varying the current in the line according to any predetermined rule or code may be substituted for the mechanism 34—41 shown in Fig. 1 and for the corresponding deciphering mechanism at the receiving end; and any means for varying the ratio of movement of the arms of the pantograph may be substituted for the gearing illustrated in Figs. 2 and 3.

What I claim is:

1. In an apparatus for enciphering graphic figures the combination of an instrument for tracing the figure to be enciphered, mechanism associated with said instrument for resolving movement of a given point in said mechanism into a plurality of components, a plurality of transmitting circuits, means for supplying said circuits with current, means for causing a variation of the current in the several circuits in response to variations in said components respectively, and means for concurrently causing other variations in said currents which are independent of the movement of said given point in accordance with the figure to be enciphered.
2. In an apparatus for enciphering graphic figures the combination of an instrument for tracing the figure to be enciphered, mechanism associated with said instrument for resolving movement of a given point in said mechanism into a plurality of components, a plurality of transmitting circuits, means for supplying said circuits with currents, means for causing a variation of the current in the several circuits in response to variations in said components respectively, and means for effecting concurrently

other variations in the currents of one or more of said circuits which are independent of the components of movement of said tracing instrument, and which follow some predetermined rule.

3. In a system for enciphering telautographic transmission of graphic figures the combination of an instrument for tracing the figure to be transmitted, a telautograph transmitter including a plurality of arms associated with said tracing instrument for causing a plurality of varying electric currents representing in value, respectively, the degree of movement of said arms, and means for causing the variations in said currents to assume instantaneous relative value other than those corresponding to movement of said arms in accordance with the figure to be transmitted.

4. A secret transmission system for graphic figures comprising an instrument for tracing the figure to be transmitted, a telautograph transmitter, including arms associated with said instrument for causing a plurality of varying electric currents representing in value, respectively, the degree of movement of said arms, means for causing variations in said currents which do not correspond to components of the movement of said tracing instrument, and a telautograph receiving apparatus, including means for counteracting the effect of said last named variations of said electric currents whereby the recording pencil of said receiving apparatus reproduces correctly the figure traced by said instrument.

5. The method of enciphering graphic figures which consists in tracing the figure, representing the tracing movement by a plurality of changing values instantaneously corresponding to components of said movements, and varying one or more of said changing values during the tracing, in accordance with some predetermined rule.

In testimony whereof, I have signed my name to this specification this 10th day of July 1923.

GILBERT S. VERNAM.
